GRID MACHINE AND THE LIKE

Cyprian A. Narwid, Harrison, N. J., assignor to
 Tung-Sol Lamp Works Inc., Newark, N. J., a
 corporation of Delaware

Application June 6, 1938, Serial No. 212,161

14 Claims. (Cl. 140—71)

The present invention relates to machines for making grids for radio tubes and comprises an improved machine of this character which is provided with means for preventing or controlling 5 the bows or bends usually present in such grids. The invention includes also a novel method of preventing or controlling during manufacture, the occurrence of such bows or bends in the grid.

Grids for use in radio tubes and the like are 10 usually manufactured by notching support wires carried by a relatively rotating mandrel, winding the grid wire into the notches and fastening the grid wire into the notches, as by swaging. The support wires after the notching, winding and 15 swaging operations of conventional practice tend to bend or depart from a perfectly straight position with the result that undesirable bows or bends are formed in the finished grids.

One object of the invention is to control the 20 degree of the bow or bend of the support wires so as to avoid the undesirable bends or bows of the prior practice and to obtain grids approaching the straight or unbent character desired in practice.

Other objects of the invention will hereinafter 25 appear.

For a better understanding of the invention reference may be had to the accompanying drawings forming a part of this application wherein:

Fig. 1 is a side elevational view partly in section of the essential mechanism of a grid machine embodying the invention;

Fig. 2 is an end view of parts thereof;

Fig. 3 is a diagrammatic side view of one part 30 of the machine;

Fig. 3a is a fragmentary view illustrating another form of mandrel;

Fig. 4 is a view indicating the undesirable bend or bow of the grid of conventional practice; and

Fig. 5 illustrates the character of the grid which 40 may be obtained according to the present invention.

Referring to the drawings, there is shown a grid machine embodying the conventional notching wheel 1 rotatably mounted between bearing screws 2 and 3 mounted in a frame 4, a conventional swaging wheel 5 suitably supported by a frame 6, a conventional spindle 7 mounted in bearing 8 and carrying a mandrel 9, supply reels 10 for supplying the support wires 11 to the mandrel grooves 9', a reel 12 for supplying the grid wire 13 and a clamping head 14 for drawing the support wires 11 along the grooves 9' of the mandrel 9.

These mechanisms operate as in conventional

practice to draw the support wires 11 from the reels 10 through the machine, beneath the notching wheel 1, and over the swaging wheel 5. The notching wheel 1 forms the notches indicated in the support wires 11 for the reception of the 5 turns of wire 13. After positioning of the wire 13 in a notch, the swaging wheel 5 fastens the grid wire firmly to the support wire by the usual swaging operation, and as indicated in dotted lines in Fig. 1 the swager 5 is movable toward and 10 away from the mandrel 9 (by a mechanism omitted for convenience in illustration) for the purpose of discontinuing at desired intervals the swaging operations; these intervals of non-swaging corresponding to the lengths into which the 15 grid is severed for use in radio tubes and the like. The mandrel 9 and clamping head 14 on the one hand and the notching wheel 1 and swaging wheel 5 on the other are relatively rotatable. In the 20 particular embodiment shown the mandrel 9 is carried by the rotating spindle 7 (with which 25 rotate the reels 10) while the notching wheel 1 and swaging wheel 5 are relatively fixed, though the wheels 1 and 5 are journaled for rotation or oscillation about their respective axes and are adjustable toward and away from the mandrel. As 30 the mandrel 9 is rotated that part of the support wires which projects above the grooves 9' in the mandrel 9 are engaged by the notching wheel 1 to form the notches and similarly the swaging wheel 35 engages the support wires at the notches to swage the grid wire 13 into fixed position on the supports.

In the production of the grids according to the conventional practice the support wires 11 tend 35 to bend towards the notched side with the resultant bow formed in the grid as indicated, slightly exaggerated, in Fig. 4. This renders the grid difficult to mount and assemble and the degree of bow or bend of the grid support wires in conventional practice cannot be predetermined with 40 any certainty.

In the embodiment of the invention herein shown a pair of pressure or holding rollers 15, disposed in advance of the wheel 1 are journaled 45 in the forked ends of lever arms 17 and caused to engage and hold the support wires 11 firmly against the bottoms of the grooves 9'. The arms 17 are pivotally mounted in suitable slots on a cellar 18 secured to the mandrel 9 and carry at 50 their other ends adjusting screws 20 which bear upon the mandrel for adjustment of the pressure exerted by the rollers 15. Clamping screws 21 are provided for locking the adjusting screws 20 in their adjusted position. The depth of grooves 9' 55

in the mandrel 9 decreases at 22 to a point where the support wires 11 project above the mandrel so as to be engaged by the rollers 15, notching wheel 1 and swaging wheel 5.

- 5 Outwardly directed pressure upon the support wires 11 beyond the swaging wheel is effected by spreading the wires slightly apart as by an increase in the dimensions of the end of the mandrel 9 or by corresponding reduction in the depth 10 of the grooves 9'. In the particular embodiment of the invention illustrated in Figs. 1 to 3, the spreading means comprise a plate member 23 of generally diamond shaped contour and with a dimension in the plane of the grooves 9' just 15 slightly greater than that of the mandrel. Plate 23 is secured, as by a screw 24, to the reduced end of the mandrel. During operation of the mechanism, the plate member 23 rotates with the mandrel and exerts an outward pressure upon 20 the support wires 11 tending to spread them slightly apart, the latter running through grooves 23' formed on the opposite edges of the plate. The displacement or spread of the support wires under the influence of the plate or spreader 23 25 is shown slightly exaggerated in Fig. 3, where the distance d between each pair of dotted lines corresponds to the resultant outward displacement or spread of each support wire. An idler steel roller 26 positioned immediately beyond the 30 spreader plate 23 and conveniently supported from the frame 4 by means of an adjustable bracket 27 carried by the bearing screw 2 is provided for engaging the outer edges of the support wires. This roller 26 rides upon the support 35 wires 11 as the latter pass thereunder and tends to return them to parallelism in opposite to the spread effected by the plate 23.

The spreading means illustrated diagrammatically in Fig. 3a comprise the end 9a of the mandrel in which the grooves for the support wires 40 are at a greater distance apart tend to spread the wires as they leave the mandrel, the spread being exaggerated for convenience in illustration.

With the proper adjustment of the mechanism 45 described, the bend or bow of the grid support wires 11 shown in Fig. 4 is substantially obviated and the straight controlled product, with parallel support wires of Fig. 5 is consistently produced. I have obtained particularly good results by the 50 use of a spreader plate 23 having a spread of from .002 to .010 inch greater than that of the mandrel, namely, with d from .001 to .005 inch. Preferably only a slight pressure should be applied through the rollers 15, sufficiently to hold 55 the wires 11 firmly in the grooves 9', and positive spread should be given the support wires by the spreader plate 23 as indicated. The roller 26 is preferably adjusted so as to return the wires to parallelism and is applied near to the place 60 at which the spreader plate contacts the wires. The roller 26 may be radially adjusted to any position desired through the adjustable connection of the slotted bracket 27 with the frame 4, it being only necessary to release and tighten the 65 nut 2' for this purpose. Thus the grids, controlled as to the straightness desired, may be obtained at will.

Thus the bend or bow of the support wires is 70 prevented or controlled by the application of radial pressure on the support wires both in advance of and beyond the notching wheel 1. Where the support wires are carried on the mandrel 9, the pressure is applied radially inward while beyond the notching wheel the pressure is 75 applied radially outward, and just beyond this

latter application of pressure, further inwardly directed pressure is applied. The effect of these various pressure applications upon the support wires is such that substantially all bending or bowing of the support wires of the finishing grid is eliminated and a controlled, uniform product, with straight support wires, such as is shown in Fig. 5, is obtained.

Obviously various changes might be made in the embodiment illustrated without departing 10 from the spirit of the invention as defined in the accompanying claims.

Certain features of the invention herein set forth are claimed generically in my copending application Serial No. 269,399, filed April 22, 1939. 15

I claim:

1. In a machine of the character set forth, relatively rotating mandrel and wire notching means, said mandrel having a longitudinal groove on the surface thereof along which supporting wire is fed, means disposed at a point in advance of the notching means for holding the wire firmly in the groove, said mandrel having a part disposed at a point beyond the notching means whose guiding groove portion is displaced from the axis of the mandrel a slightly greater distance than the part of the groove disposed at the point where the notching means is located and a relatively rotating idler wheel disposed at a point beyond said guiding groove portion and journaled on an axis substantially parallel to the axis of the mandrel with the periphery of the wheel projecting towards the axis of the mandrel to a point slightly beyond the last named mandrel grooved guiding portion. 25

2. In a grid machine of the type having relatively rotatable mandrel and wire notching means and means for feeding support wire along the mandrel and feeding grid wire to the notches formed by the notching means, in combination, a roller engaging the support wire at a point in advance of the notching means and holding the same against the mandrel at said point, means carried by said mandrel at a point beyond the notching means and engaging the support wire in a manner to cause a slight bend thereof in a direction opposite to the direction of pressure exerted by the roller and a roller disposed beyond the notching means and engaging the support wire in a manner to cause a slight reverse 50 bend in said support wire as the support wire is drawn along the mandrel. 40

3. In a grid machine of the type having relatively rotatable mandrel and notching means and means for feeding a support wire along the mandrel and feeding grid wire to the notches formed by the notching means, in combination, means for engaging the support wire at a point in advance of the notching means and holding said support wire firmly against said mandrel at said point, said mandrel having means thereon disposed at a point on the opposite side of the notching means from said holding means and engaging the support wire in a manner to cause a slight bend thereof in a direction opposite to the pressure applied by the holding means and means disposed further beyond the notching means for engaging the support wire and setting up therein a slight reverse bend as the support wire is fed along the mandrel. 55

4. In a grid machine of the type having relatively rotatable mandrel and notching means and means for feeding support wires along the mandrel and feeding grid wire to notches formed by the notching means, in combination, means en- 70

75

gaging said support wires at points in advance of the notching means and holding the same firmly against the mandrel at said points, said mandrel having spreading means disposed at a point beyond the notching means and engaging the support wires in a manner to cause a slight spreading of the same at that point, and means disposed at a point slightly beyond said spreading means and engaging said support wires in a manner 10 to cause a slight reverse bend therein as the support wires are fed along the mandrel.

5. In a machine of the character set forth, a rotating mandrel having a longitudinal groove on the periphery thereof, means for feeding a support wire along said groove, means for forming notches in said support wire as the latter is fed along said mandrel, means for feeding grid wire to said support wire and fastening the same in said notches, an adjustable roller engaging said support wire at a point in advance of the notching means and holding said support wire firmly in said groove, said mandrel comprising at a point beyond the notching means a part for engaging the support wire which is of slightly 15 greater radial dimensions than the similar dimension of the mandrel at the notching point and a radially adjustable idler wheel disposed beyond said part and engaging said wire to cause a slight inward bend therein as the support wire 20 is fed along the mandrel.

25. 6. In a grid machine of the type having relatively rotatable mandrel and wire notching means and means for feeding support wire along the mandrel and feeding grid wire to the notches formed by the notching means, in combination, a roller engaging the support wire at a point in advance of the notching means and holding the same against the mandrel at said point, a spreader plate disposed on the opposite side of 30 the notching means from said roller and engaging said support wire in a manner to apply a slight outward bend thereto and a roller disposed beyond the spreader plate and engaging said support wire in a manner to cause a slight reverse bend of the support wire as the latter is 35 moved along the mandrel past the spreader and the last named roller.

40. 7. In a machine of the character set forth, relatively rotating mandrel and wire notching means, said mandrel having a longitudinal groove 45 on the surface thereof along which supporting wire is fed, said mandrel having a part disposed at a point beyond the notching means whose guiding groove portion is displaced from the axis of the mandrel a slightly greater distance than the part of the groove disposed at the point where the notching means is located and a relatively 50 rotating idler wheel disposed at a point beyond said guiding groove portion and journaled on an axis substantially parallel to the axis of the mandrel with the periphery of the wheel projecting towards the axis of the mandrel to a point slightly beyond the last named mandrel grooved 55 guiding portion.

60. 8. In a grid machine of the character set forth, comprising relatively rotatable mandrel and notching means, and means for feeding support wire along the mandrel and for feeding grid wire 65

to the notches formed by the notching means, the provision of means positioned in advance of the notching means for pressing the support wires inwardly against the mandrel and means beyond the notching means for exerting an oppositely directed pressure upon the support wires, said last mentioned means including a spreader plate secured to the mandrel and additional means for applying pressure to the support wires, said additional means comprising a roller positioned adjacent the spreader plate to contact said wires and to exert a pressure thereon opposite to that exerted by the spreader plate and subsequent thereto.

5. 9. In a grid machine of the type having a rotatable mandrel, notching means and a supporting member therefor, means for feeding support wire along the mandrel and for feeding grid wire to the notches formed by the notching means, the combination comprising adjustable rollers engaging the support wires and applying unyielding pressure thereto at points in advance of the notching means, a spreader plate secured to the mandrel and applying oppositely directed pressure to the support wires at points beyond the notching means and a roller mounted on the supporting member for the notching means just beyond the point of engagement of said spreader plate with the support wires for exerting inwardly directed pressure upon the support wires. 30

10. 10. In a grid machine of the type having relatively rotating mandrel and notching means, means for feeding a pair of support wires along the mandrel and for feeding grid wires to the notches formed in said support wires by said notching means, the combination comprising means in advance of the notching means for applying pressure to the support wires radially of the mandrel and means beyond the point at which grid wire is supplied to the support wires for 35 spreading the support wires slightly apart. 40

11. A machine according to claim 10 wherein said last mentioned means forces said support wires substantially from .002 to .010 inch apart.

12. A machine according to claim 10 including 45 means adjacent to and beyond said spreading means for applying a pressure to said support wires in a direction tending to return said wires to parallelism.

13. A machine of the character set forth in 50 claim 8, comprising means for exerting pressure against the support wire at a second point beyond the notching means.

14. In a grid machine of the character set forth comprising relatively rotatable mandrel 55 and notching means and means for feeding support wire along the mandrel and for feeding grid wire to the notches formed by the notching means, the provision of means for exerting pressure against said support wire at a point beyond the notching means and in the opposite direction to the pressure applied by the notching means, and means for engaging said support wire and applying pressure thereto at another point still further beyond said notching means and in 60 the same direction as that exerted by the notching means. 65
